UNITED STATES PATENT OFFICE.

ISAAC CLINTON GRAY, OF LA FAYETTE, INDIANA.

HINGE.

1,294,793.

Specification of Letters Patent. Patented Feb. 18, 1919.

Application filed January 12, 1918, Serial No. 211,608. Renewed December 28, 1918. Serial No. 268,780.

To all whom it may concern:

Be it known that I, ISAAC C. GRAY, a citizen of the United States, residing at La Fayette, in the county of Tippecanoe and State of Indiana, have invented new and useful Improvements in Hinges, of which the following is a specification.

This invention relates to a hinge and particularly to a hinge which is especially adapted for use in connection with closure members which are to swing in both directions.

The primary object of the invention is to provide an inexpensive hinge of this character which can be more easily applied and is less likely to get out of order than are the hinges now in use and is so constructed that the hinge will automatically act to restore the closure member to its normal position when the closure member has been opened.

Another object of the invention is to provide the hinge wherein the leaf for connection with the closure member is in the form of a yoke on the arms of which are lugs, which through their engagement with a spring pressed bar carried by the other leaf of the hinge not only normally prevent casual swinging movement of the closure member, but act as levers to be acted upon by the bar when moving the closure member to a position to obstruct the opening in which the closure member is mounted.

A further object of the invention is to so construct the leaf of the hinge which is in the form of a yoke that anti-friction devices may be used in connection with the hinge.

With these and other objects in view, the invention resides in the novel combination and arrangement of parts, which will be hereinafter described and particularly pointed out in the claims.

The preferred embodiment of the invention has been illustrated in the accompanying drawings, although no restriction is necessarily made to the precise details of construction therein shown, as changes, alterations, and modifications within the

scope of the claims may be resorted to when desired.

In the drawings:

Figure 1 is a view in side elevation of a portion of a door way wherein the door is connected with the door frame by a hinge constructed in accordance with the invention.

Fig. 2 is a horizontal section upon an enlarged scale on the line 2—2 of Fig. 1.

Fig. 3 is a section on the line 3—3 of Fig. 2.

Fig. 4 is a perspective view of one of the leaves of the hinge.

Fig. 5 is a similar view of the other leaf of the hinge.

Fig. 6 is a detail perspective view of the spring pressed bar carried by one of the leaves of the hinge.

Fig. 7 is a detail perspective view of the portion of one of the hinge leaves showing a modification of the invention.

Like characters of reference denote corresponding parts throughout the several views in the drawings.

Referring now to the drawings in detail the letter A designates a portion of a door frame wherein a door B is connected with a frame C by the hinge which is constructed in accordance with my invention and not only permits the door B to swing in both directions but automatically acts upon the door to restore the same to normal closed position after the door has been opened.

The hinge includes leaf member which comprises a rectangular shaped plate 12 which is retained within a recess in the frame C by screws 13. The plate 12 has formed upon one side thereof a central cylindrical housing 14 which extends within a mortise in the frame C and is exteriorly threaded for a portion of its length. Threadedly engaged with the housing 14 to permit its adjustment thereon is a cap 15 in the closed end of which is formed a central opening alining with a similar opening 17 in the plate 12.

Extending within the housing 14 through the opening in the cap 15 is a bar 18

having formed thereon at one end an enlarged head 19 which is arranged within the opening 17 in the plate 12 and extends beyond the outer face thereof. The bar 18 is yieldably held against sliding movement in the housing 14 by a coiled expansion spring 20 which is mounted upon the bar to bear against the head 19 and the closed end of the cap 15. The tension of the spring 20 on the bar 18 may be regulated through the adjustment of the cap 15 on the housing 14.

Formed on the outer face of the plate 12 and arranged upon opposite sides of the opening 17 are a pair of lugs 21 with each lug provided with a circular head 22 in which is formed a ball race 23.

The other leaf of the hinge comprises a yoke 24 between the arms 25 and 26 of which 20 extends the door B which is connected with the arms of the yoke by screws 27. The yoke 25 serves as a closure member for a recess 29 in the closure B in which are received the circular heads 22 on the lugs 21 on the 25 outer face of the plate 12, said lugs extending within slots 32 in the closed end of the yoke which slots extend into the arms 25 and 26. Arranged in the race ways 23 are bearing balls 34 which are engaged by webs 33 30 formed integral with the arms of the yoke 24 and act as braces therefor. A hinge pin 35 passes through suitable openings in the heads 22 and the webs 33 and the housing 40 of the yoke and acts as a pintle about which 35 the yoke 24 may turn.

The head 19 on the bar 18 extends into the recess 29 and also through a central slot 36 in the closed end of the yoke 24 and into the housing of the yoke 40, Fig. 3, and is 40 normally held in contact with a pair of projections or lugs 37 on the arms of the yoke by the spring 20.

Through the provision of the spring 45 pressed bar 18 and the lugs 37 on the leaves of the hinge it is apparent with reference to the drawings that the closure member B is normally held against casual swinging movement by the bar 18, while when the door has been moved to open position a lug 37 50 will act as a lever to be acted upon by the bar 18 for restoring the door to a position in which it will obstruct the opening in which it is mounted.

By virtue of the bar 18 in one leaf or 55 member of the hinge being provided with the horizontally-disposed head 19, and the other leaf or member of the hinge being equipped with lateral lugs 37 in engagement with the face of said head 19, the head is 60 enabled to exert considerable leverage and promptly close the door. It will also be noted that the disposition of the head 19 in the housing 40 of the door leaf or member, and the extension of the pintle 35 through 65 said housing, assure the hinge leaves or

members being strongly retained in proper relative positions for efficient action of the spring-backed head against the lateral lugs 37.

In the modified form of the invention disclosed in Fig. 7 in the drawings the leaf, or yoke 24 is identical in construction with that disclosed in the preferred form of the invention with the exception, that in the modified form of the invention lugs 37 are bifurcated and have mounted in the slots therein rollers 38 which bear on the head 19 on the bar 18.

From the foregoing description taken in connection with the accompanying drawings 80 it is apparent that a hinge for the purpose set forth has been provided which is easy to apply, durable in use, and inexpensive of manufacture.

Having thus described the invention, what 85 is claimed as new, is:—

1. In a hinge, the combination of a member having a horizontally slotted plate, an abutment carried by and spaced from the rear of the plate and forwardly-extending horizontally-disposed lugs, a bar having a head movable in the slot of the plate and also having a portion guided in the said abutment thereof, a spring surrounding the bar and interposed between the head and 90 said abutment, a second member having means receiving the said lugs of the first-named member and superimposed thereon and lateral portions opposed to the face of the head on the bar, and a pintle extending 95 through the members and connecting the same together.

2. In a hinge, the combination of a member having a horizontally slotted plate, an abutment carried by and spaced from the 105 rear of the plate and forwardly-extending horizontal lugs, a bar having a head movable in the slot of the plate and a portion guided in the said abutment thereof, a spring surrounding the bar and interposed 110 between the head and said abutment, a second member, of general yoke form, having slots receiving the lugs of the first named member and webs opposed to said lugs and a housing loosely receiving the head on the 115 bar, and lateral portions opposed to the face of said head, and a pintle extending through and effecting pivotal connection of the webs and housing of the second named member to the lugs of the first named member.

3. In a hinge, the combination of a member having a horizontally slotted plate, an abutment carried by and spaced from said plate and forwardly extending lugs carried by said member and provided with circular 125 grooves in the upper sides thereof, a bar having a head movable in the slot of the plate and a portion guided in the said abutment thereof, a spring surrounding the bar and interposed between the head and said 130

abutment, a second member of general yoke form having slots receiving the lugs of the first named member and webs opposed to said lugs, a housing loosely receiving the 5 head on the bar, and lateral portions opposed to the face of said head; the back wall of the housing and the lateral portions describing an obtuse angle, anti-friction means in-

terposed between the lugs of the first named member and the webs of the second named 10 member, and a pintle extending through the said lugs, webs and housing of the members and effecting pivotal connection thereof.

In testimony whereof I affix my signature.

ISAAC CLINTON GRAY.
